UNITED STATES PATENT OFFICE.

STERLING ELLIOTT, OF NEWTON, MASSACHUSETTS.

ADDRESSING-MACHINE.

1,025,459.

Specification of Letters Patent.

Patented May 7, 1912.

Application filed March 9, 1909. Serial No. 482,351.

To all whom it may concern:

Be it known that I, STERLING ELLIOTT, of Newton, county of Middlesex, State of Massachusetts, have invented an Improvement in Addressing-Machines, of which the following is a specification.

This invention relates to addressing-machines in which a series of stencil-plates are moved into and out of position to coöperate with printing-devices by which addresses are printed on envelopes, bill-heads and other things.

The invention has for its object to rigidly connect together the component parts of the receptacle which is adapted to contain a pile of stencil-plates, whereby it may be applied to or removed from its support in assembled condition; also, to make said receptacle reversible, whereby it may be arranged to face forward or rearward as may be required; also, to provide the receptacle which contains the pile of stencil-plates, or either of them, if two are employed, with means for assisting the entry thereinto or the removal therefrom of the pile of stencil-plates, whereby displacement of the plates of the pile may be prevented and their order preserved; also, to provide means for supporting the receiving-receptacle for the stencil-plates close to the printing-devices, which does not obstruct the top of the table, so that an unobstructed space of large area is provided on top of the table to receive the object to be printed; also, to improve the construction of the sliding-pusher by which the lowermost stencil-plate of the pile is removed from the receptacle, and the means for supporting it and for guiding it, and to utilize the guides for the pusher as supports for the pile of stencil-plates contained in the receiving-receptacle; also, to provide a reciprocating-frame bearing the sliding-pusher and operating-means therefor, which is movable into and out of engagement therewith, and a controlling-device for controlling the engagement of said operating-means with the reciprocating-frame, whereby the pusher may be operated to move along the stencil-plates and cause them to rest in transit for different periods of time according as it is desired to print one or more addresses with each stencil-plate; also, to provide the machine with improved means for reversing the stencil-plates so

that when taken successively from one pile and formed into another pile their order will be preserved; also, to arrange the reversing-device for the stencil-plates adjacent the discharging-receptacle and to provide the latter with an entrance at the bottom and an exit at the top and to provide means for successively transferring the stencil-plates from the reversing-device to the bottom of the discharging-receptacle; also, to provide improved means for operating the reversing-device for the stencil-plates; also, to provide improved means for moving the reversed stencil-plates into the discharging-receptacle, at the bottom thereof; also, to provide an improved form of discharging-receptacle especially adapted to receive the stencil-plates at the bottom, so that the pile contained therein may be formed from the bottom up; also, to provide an obliquely arranged arm bearing the impression-roll, the support for which is arranged at one side of the inking-mechanism, and to provide improved means for supporting said inking-mechanism, whereby a large unobstructed space is provided on top of the table for the work to be printed; also, to attach the support for the impression-roll to the arm bearing it by means whereby said support may rock with respect to the arm, to permit the roll to engage the stencil-plates with an even pressure throughout its length.

Figure 1 is a plan view of an addressing-machine embodying this invention. Fig. 2 is a front elevation of the machine shown in Fig. 1. Fig. 3 is a vertical section of the machine shown in Fig. 2, taken on the dotted line $x-x$. Fig. 4 is an enlarged plan view of one of the receptacles for the stencil-plates. Fig. 5 is an enlarged longitudinal sectional detail of a portion of the left-hand end of the machine, showing particularly the receiving-receptacle, its support, and means for moving the stencil-plates successively from the bottom of a pile contained in said receptacle and controlling-mechanism for said plate-moving means. Fig. 6 is a transverse sectional detail of the sliding-pusher and means for operating it, taken on dotted line 6-6, Fig. 7. Fig. 7 is a longitudinal sectional detail of the operating means for the sliding-pusher. Fig. 8 is a detail of the controlling-means for operat-

ing the sliding-pusher. Fig. 9 is an enlarged longitudinal section of a portion of the machine, showing particularly the reversing-device for the stencil plates and the discharging-receptacle. Fig. 10 is a transverse sectional detail of the reversing-device taken on the dotted line $z-z$, Fig. 9. Fig. 11 is a detail to be referred to. Fig. 12 is a side view of the inking-mechanism for the 10 impression-roll, the parts being in their normal positions. Fig. 13 is a vertical section of the inking-mechanism shown in Fig. 12, the parts being in the positions they will occupy when the impression-roll is in engagement with a stencil-plate. Fig. 14 is a 15 detail of the base-plate for the stencil-plate receptacle.

1 represents a table which is supported by suitable legs. It is provided at each end 20 with a receptacle for a pile of stencil-plates, and means are provided for transferring the stencil-plates from one receptacle to the other, said means, operating intermittently, whereby the stencil-plates are moved successively and are caused to stop in transit long 25 enough to be engaged by an impression-roll in order that addresses may be printed on envelopes or other things. The receptacle at one end of the machine is termed the "receiving-receptacle," and the receptacle at the opposite end of the machine the "discharging-receptacle."

Each receptacle, as here shown, consists of several upright posts arranged to inclose 35 a space of the shape and size of the stencil-plates, there being two angularly formed corner-posts 3, 4, at the rear side and a flat post 5 at the middle of the front side. Said posts are made of a length to correspond to 40 the height of the pile of stencil-plates which it is intended they shall support. The posts of each receptacle are rigidly connected together, so that the receptacles thus constructed may be removed from or applied 45 to supports which are provided for them on the machine. As here shown said posts are rigidly secured to a quadrangular base-plate 150, see Fig. 14, which is made as an open frame, and the corner-posts 3, 4, have feet 50 152 which extend along the tops of the side-bars of said base-plate and are secured thereto. The two receptacles are made substantially alike, and they are also made reversible in order that their positions on their 55 supports may be reversed, the corner posts being either at the rear or at the front. To provide for thus reversing the receptacles the front and back bars of the base-plate 150 each have a hole for an attaching-screw 60 153, and also have one or more dowel-pins 154, and said support is provided with holes for said screws and dowel-pins. In Fig. 4 the receptacle is represented in full lines in one position and in dotted lines in its 65 reversed position. The top of one of the bars

of the base-plate 150 is recessed intermediate its length in order that the lowermost stencil-plate of a pile may be engaged by the fingers for the purpose of lifting the pile from the receptacle.

As the stencil-plates of a pile are arranged in regular order and it is desired to preserve this order, means are provided for guiding the pile of stencil-plates into and out of the receptacle, to prevent displacement of the plates of the pile. Such means, as here shown, consists of a guide-bar 6, see Fig. 3, arranged between and pivotally connected to the upper ends of the corner-posts 3 and 4, and adapted to be moved into and out of vertical position as may be required. When in vertical position it occupies a position above the space between said corner-posts, although in the same plane, and serves as a rest or guide against which the pile of stencil-plates is held while being lowered into or lifted from the receptacle. At other times it will be turned back out of the way, as shown in Fig. 3. Without said guide-bar there is great difficulty in handling the piles 85 of stencil-plates, as they are heavy and the plates of the piles are liable to become displaced, or the whole pile is liable to buckle.

The receiving-receptacle at the left hand side of the machine is arranged on a support, herein shown as a plate 2, which is secured to the top of the table 1, and the under side of said plate is cut away at its inner end, see Figs. 2 and 5, to thereby form an overhanging portion, which extends over 100 the top of the table, and provides beneath it an unobstructed space 7 into which the object to be printed may extend. The receiving-receptacle is arranged on top of the overhanging portion of said supporting-plate 2. By thus forming the supporting-plate the receiving-receptacle may be disposed quite close to the printing-device, to be described, and yet an unobstructed space 105 of large area provided on top of the table 110 for the object to be printed.

The receiving-receptacle is open at the bottom, from side to side, above its supporting-plate, to provide for the removal of the lowermost stencil-plate of the pile, which removal is accomplished by means of a sliding-pusher, and the side-bars of the base-plate 150 are cut away at their under sides, as at 151, to provide for said pusher. The pusher consists of a plate 8, see Figs. 1 and 6, arranged horizontally in a longitudinal recess formed in the top of the supporting-plate 2, and which extends from end to end thereof. It is movable longitudinally in said recess and is supported upon and guided by ribs 9, 9, arranged at opposite sides of said recess, which enter grooves formed in its opposite sides. Said ribs 9, 9, extend from end to end of the plate 2, and hence extend beneath the receiving-receptacle.

tacle, being arranged in the cut away portions 151, formed in the under sides of the side-bars of the base-plate 150. The pile of stencil-plates contained in said receptacle rests on said ribs. A pair of grooved guide-bars 19, 19, extend from the receiving-receptacle to the opposite end of the table 1, or thereabout, which are arranged in line with said guide-ribs 9, 9, and parallel with the top of the table. They are arranged with their grooved sides facing each other to receive between them the stencil-plates, and together they form a slide-way along which said plates are moved. The pusher 8 is movable from a position at the left hand side of the receiving-receptacle to a position beneath said receptacle and its end engages the left hand end of the lowermost stencil-plate of the pile and moves said plate along on the guide-ribs 9, 9, into the slide-way 10, 10. The movement of the pusher 8 is sufficient to entirely remove the lowermost stencil-plate from the receptacle, so that when it resumes its normal position the pile of stencil-plates above it is permitted to settle down on the guide-ribs 9, 9, in order that the next plate of the pile, which becomes the lowermost plate thereof, may occupy a position in front of the pusher, to be engaged by the pusher on its next stroke. The pusher is operated intermittently, and the stencil-plates are successively removed from the receptacle to the slideway, and each plate in the slideway engages and moves along the plate ahead of it during each operation of the pusher, thus the entire row of stencil-plates contained in the slideway is moved along intermittently.

The pushing-plate 8 is rigidly connected by a link or arm 12, see Figs. 1, 5, 6, and 7, with a reciprocating-frame, whereby it may be reciprocated. Said reciprocating-frame consists of a flat bar 13, arranged horizontally in guideways provided for it on the under side of the table 1, having on its upper side, at or near one end, a boss 14, which projects up through a slot in the table, and a narrow bar 15 arranged beneath said bar 13, having upwardly extended ends which are attached to the opposite ends of said bar 13. The link or arm 12 is secured to said boss 14. Said frame is adapted to be engaged and disengaged by the operating means which is provided for reciprocating it, so that while said operating means may continue to operate, said frame may or may not be moved by it. Said operating means, as here shown, comprises a long bar 16, see Figs. 2 and 5 having a loop-like end portion 17, horizontally arranged beneath the table 1. The bar 15 extends through said loop 17, see Fig. 7, and the end of the loop rests by gravity on said bar 15. One end of the bar 16 is thereby supported. Said bar 16 is designed to be reciprocated longitudinally,

and when thus moved the end of the loop 17 slides along on the bar 15, or enters a notch 18, formed in said bar 15, and moves said bar 15 with it, according to whether it is permitted to or prevented from entering said notch. The opposite end of said bar 16 is pivotally connected to the upper end of an upright arm 19 of a bell-crank lever, pivoted at 20 to the frame-work, the other arm 21 of said lever being connected by a rod 22 to the arm 23 of a bell-crank lever, pivoted at 24 to the frame-work, the other arm 25 of said last named lever being connected by a link 26 with an arm 27 extending from the upper end of a rod 28, which is connected with a crank-pin 29 projecting from one side of a gear-wheel 30 secured to a shaft 31. A pinion 32 engages said gear-wheel 30, which is secured to a shaft 33, bearing a friction-disk 34, engaged by a friction-roll 35, driven by a friction-disk 36 adapted to receive upon it a belt, or to be otherwise driven. As the bell-crank lever 19, 21, is vibrated by the power-actuated means thus described, the bar 16 will be reciprocated longitudinally.

When it is desired to use each stencil-plate once the row of stencil-plates will be moved along the slideway at each operation of the pusher, and, in such case, the operating-means for the reciprocating-frame bearing the pusher will remain continuously in engagement therewith, as for instance, the loop 17 carried by the bar 16 will remain continuously in engagement with the notched bar 15, but when it is desired to use each stencil-plate more than once said operating-means will be temporarily disengaged from the reciprocating-frame, so that said frame will remain at rest and the pusher will not be operated to feed along the stencil-plates, although the operating-means will continue to operate independently thereof. While temporarily disengaged from the reciprocating-frame bearing the pusher, the bar 16 will be reciprocated longitudinally, the same as when in engagement with said frame, but the end of the loop 17 will slide along on top of the bar 15, which latter is made long enough to provide for such independent longitudinal movement of the bar 16.

To provide for controlling the engagement of the operating-means with the reciprocating-frame bearing the pusher, whereby said frame may be continuously engaged or temporarily disengaged at regular or other intervals automatically operated means are herein shown.

Referring to Figs. 5 and 8, a closing-plate 37, for the notch in the bar 15 is employed as a controlling-device, which is pivoted at 38, and arranged to be raised and lowered to cover and uncover said notch. Said closing-plate bears a detent 39 which engages the notched edge of a disk 40, which disk is

adapted to be intermittently revolved, and while revolving acts to raise and lower the closing-plate. When the detent 39 enters one of the notches in the disk the closing-plate will fall by gravity into its lowermost position, and the notch 18 will be uncovered, and when the detent rests on the edge of the disk between the notches, said closing-plate will occupy its uppermost position and said notch will be covered. The notches may be arranged on the disk in any desired manner according as it is desired to operate the closing-plate to cover and uncover the notch 18, and several disks may be provided 15 with the machine having notches differently arranged on their peripheries and the substitution of one for another may be made as required. The disk is arranged on the free end of a stationary bar 47, and is detachably held thereon by a suitable nut, and for the purpose of intermittently revolving it a ratchet-wheel 41 is also arranged on said bar which is adapted to be detachably connected with said disk, and which is engaged 20 by a pawl 42, pivotally connected to a pawl-carrier 43, extended from a sleeve 48 mounted on said bar 47. Said pawl-carrier is connected by a rod 44 with the arm 25 of one of the bell-crank levers of the machine, or it 25 may be connected to some other movable part thereof. The rod 44 is reciprocated longitudinally to thereby cause the pawl to repeatedly move the ratchet-wheel and thereby intermittently rotate the disk. A disk 30 45, see dotted lines Fig. 5, may be arranged on the bar 47, and connected with the ratchet-wheel and also with the disk 40, said disk 45 having peripheral notches arranged at regular distances apart, corresponding to 35 the teeth of the ratchet, and its notched edge is continuously engaged by a flat spring 46, for the purpose of holding the rotatable parts in predetermined positions at each movement of the ratchet-wheel. The notched disk 45 is herein shown as interposed between the ratchet-wheel 41 and the notched disk 40, and said three members are connected together by a pin projecting from the ratchet-wheel which extends through a hole in the disk 45 and into or through a hole in 40 the disk 40.

The disk 40, shown in Figs. 5 and 8, is arranged to provide for using each stencil-plate twice, it having one half as many notches on its periphery as there are teeth on the ratchet-wheel, so that the detent 39 will enter one of the notches on the disk 40 as the ratchet-wheel is moved one step, and will rest on the edge of the disk between the notches when the ratchet-wheel is moved the next step, and so on.

By the means herein described the stencil-plates are moved along the slideway intermittently, each moving along the one ahead of it, and resting, in transit, for short periods

of time, to enable the printing-device, to be described, to operate and print with each stencil-plate one or more addresses as may be required.

Means are also herein shown whereby the closing-plate 37 for the notch 18 may be continuously held in either its upper or lower position, so that the reciprocating-frame bearing the pusher will be continuously engaged by the operating means or will be continuously disengaged, whereby each stencil-plate may be used but once, or a single stencil-plate may be used as many times as desired. Said means, as herein shown, consists of a hand-wheel 160 secured to the pivot-shaft of the pawl 42, which may be turned to throw said pawl out of engagement with the ratchet-wheel 41, as represented by dotted lines Fig. 5.

As the stencil-plates arrive at the opposite end of the slideway, at the right hand of the machine, they are delivered to a reversing-device by which their position is reversed, that is to say, they are turned upside down. They are then transferred from said reversing-device to the discharging-receptacle. They are thrust forward into said receptacle at the bottom, so that the pile is formed therein from the bottom upward; and the stencil-plates of the pile are arranged in the same order as taken from the receiving-receptacle except the position of the pile is reversed, but when the pile is taken from the discharging-receptacle and is turned upside down it is then ready to be again placed in the receiving-receptacle. Thus the order of the stencil-plates of the pile is preserved. The reversing-device is located at the end of the slideway, being at the ends of the guide-bars 10, 10, which terminate at the right hand side of the table 1, and as the stencil-plates leave said guide-bars and enter the reversing-device their movement is slightly retarded by means of a spring-finger 49, which is arranged above at least one of the guide-bars and is adapted to bear yieldingly upon the stencil-plates.

The reversing-device, see Figs. 9 and 10, consists of an intermittently revolving plate-support adapted to receive the stencil-plates one at a time from the slideway and by revolving to reverse them, and a frame bearing said plate-support having a plate-receiving recess beneath said plate-support adapted to receive the plates from the plate-support, and means for transferring the plates from the plate-receiving recess to the discharging-receptacle.

The plate-support consists of a frame, made hollow and open for lightness, and having at its opposite sides flat faces 51, 51, adapted to receive upon them the stencil-plates, and also having at its opposite sides projections 52, 52, arranged at opposite sides of the flat faces, to receive the stencil-

plates between them. The projections extend at right angles to the flat faces or thereabout. The sides of the frame are circularly formed and arranged concentric to its axis. Said frame is secured to a horizontal shaft 53 which has its bearings in supports provided beneath the table 1, and which extends into the supporting-frame, and by said shaft is intermittently revolved, turning a half revolution at each operation of the shaft but always in the same direction, so that its faces are repeatedly reversed by said shaft.

The supporting-frame comprises a base 54 having a pair of upright walls 55, 55, rising from it and spaced apart sufficiently to receive between them the rotatable plate-support, said upright walls each having an opening through it opposite the plate-support. A plate 56, pivotally connected to one of the upright portions 55, enters the side opening therein and rests against the plate-support. Said pivoted plate 56 is spring-pressed and as the plate-support revolves it moves inward and outward following the general contour of said plate-support, and by engaging the stencil-plate held by said support acts to hold the plate from falling out while the plate-support is being overturned, until the stencil-plate passes by the end of said plate 56. Unless said plate 56 or some equivalent device is provided for holding the stencil-plate on its receiving-face 51 as the plate-support revolves, said stencil-plate is liable to fall out and its correct reversal is not insured. A cover 57 closes the side opening in the other upright wall 55. Upon lifting the cover access may be had to the revolute plate-support.

The plate-support is held a suitable distance above the base of the supporting-frame to provide a recess 165 beneath it, of suitable shape and size to receive the reversed plates as the plate-support is turned over. The shaft 53 bearing the plate-support is designed to be revolved intermittently to thereby intermittently revolve the plate-support, so as to rapidly reverse its position. To thus operate said shaft 53 it is here shown as having secured to it, at or near one end, a toothed wheel 58, see Fig. 11, which is adapted to be engaged by a pawl 59 pivotally supported on an ear on the end of a sleeve 60, which is mounted loosely on the shaft. Rotary movement of the sleeve operates to cause the pawl 59 to operate the toothed wheel 58, and thereby rotate the shaft 53. Said sleeve 60 is here shown as having a spiral groove 61 extending from end to end thereof or thereabout, which receives a stud 62, with or without a roll thereon, attached to a boss 63, arranged on the end of a sliding-bar 64, movable in a guideway 65 on the under side of the base 54. Longitudinal reciprocating movement

of said bar 64 operates to reciprocate the sleeve 60 rotarily, and to thereby intermittently revolve the shaft 53.

The sliding-bar 64 has a depending ear 66 to which one end of a connecting-rod 67 is loosely connected, the other end of said rod being connected to the upright arm 19 of one of the bell-crank levers, heretofore described, so that longitudinal reciprocating movement is imparted to the sliding-bar by said bell-crank lever. The connecting-rod 67 may be composed of two members flexibly connected together, and, as here shown, said members are telescopically arranged and a spring is interposed between them which serves as the flexible connection. As the sliding-bar 64 is thus longitudinally reciprocated the plate-support is intermittently revolved and its position thereby reversed. Backward movement of the plate-support is prevented by a pawl 69 engaging a toothed-wheel 70, secured to the shaft 53. As the stencil-plates are pushed into the reversing-device they fall upon the uppermost flat face 51 of the plate-support, and as said support is reversed, they fall upon the bottom of the plate-receiving recess 165, preparatory to being thrust into the bottom of the discharging-receptacle. The discharging-receptacle is arranged adjacent the reversing-device and has an opening at the bottom, as at 75, for the entry thereinto of the stencil-plates. The sides 76 of said opening are inclined so that the stencil-plates will be guided in an upward direction by said inclined sides to thereby enter the discharging-receptacle beneath the pile of stencil-plates which has been accumulated therein. The stencil-plates are pushed forward up the inclined sides 76 by a pusher, which, as here shown, consists of a horizontal bar 80, connected to the sliding-bar 64, and arranged to be pushed through side openings in the plate-receiving recess, to thereby engage the end of a stencil-plate reposing on the bottom of said recess and move it along and up the inclined sides 76 beneath the pile of stencil-plates in the discharging-receptacle. The end of said pusher 80 is provided with a shoe 81 especially designed to engage the end of the stencil-plate and lift said end into engagement with the end of the pusher. The means herein shown for reversing the stencil-plates may be advantageously employed for reversing other things, such as printing-plates and cards, hence my invention is not limited to its use in connection with stencil-plates.

A hole is made through the table 1 at a point intermediate its length, as at 90, see Fig. 3, into or up through which a platen 91 is moved to engage the under side of a stencil-plate, and the slideway for the stencil-plates extends over said hole in order that the stencil-plates may be successively moved

over it, so as to be engaged by the platen. The platen 91 is of any suitable construction and is arranged on or formed integral with a plate 92, see Fig. 2, which is adjustably supported at the extremity of an arm 93, pivoted at 94, to an ear 95, on the under side of the table. Movement of the arm up and down correspondingly raises and lowers the platen. The arm 93 is connected by a rod 96 with an arm 97 pivoted to a fixed arm 99 on the frame, and said arm 97 has an extension 100 provided with a laterally extended pin 101, with or without a roll thereon, which enters a cam groove 102 formed in one side of the toothed gear 30. As said gear revolves the platen-carrying arm is moved up and down on its pivot.

The impression-roll 105 of an inking device is arranged above the table and is movable toward and from the platen. It is journaled in a yoke 106 secured to the extremity of an arm 107 by a single bolt, whereby said yoke may be moved with respect to the arm bearing it to enable the roll to engage the stencil-plate with an even pressure throughout its length. Said arm 107 rises from a sleeve or hub 108, see Fig. 1, mounted on a horizontal shaft 109, which is stationarily supported in a frame 123 arranged on the table 1. Said sleeve is located remote from the impression-roll, and the arm 107 is made quite long and extends over the top of the table so as to support the impression-roll above the platen and provide a large unobstructed space on top of the table for the work to be printed. The impression-roll is moved up and down by rocking the sleeve 108, and to accomplish this result an arm 110 is secured to said sleeve, which arm extends down through a hole in the table and is so formed as to permit of its connection by a pin 112 with an extension on the connecting-rod 28, and as said rod is moved by the revolving toothed-gear 30 said arm 110 will be raised and lowered and the sleeve 108 bearing it rocked.

As the impression-roll 105 moves toward and from the platen it likewise moves into and out of engagement with the inking-mechanism by which it is supplied with ink.

A convenient form of inking mechanism for purposes of illustration is shown in Figs. 12 and 13. The impression roll 105 is movable into and out of engagement with the delivering-roll 113, journaled in the yoke 114 attached to the extremities of a pair of arms 115. The inking mechanism is mounted on the stationary shaft 109 which is extended from the frame 123, and the extension of said shaft is arranged sufficiently above the table to provide ample space beyond it for the work to be printed. A distributing-roll 116 is journaled in said arms 115 which is in continuous engagement with said delivering-roll 113. The arms 115 and

yoke 114, rigidly connected thereto and bearing respectively the rolls 116 and 113, serve as and constitute a movable frame for said rolls. Said frame is raised and lowered on the shaft 109 as its axis, by the engagement therewith of a vibrating member. As here shown, the arm 107 bearing the impression-roll is selected as the vibrating member, it having attached to it a finger 117 which extends beneath an adjusting-screw 118 supported by an ear 119 on one of the arms 115, so that when said arm 107 is raised said finger will engage said adjusting-screw 118, and will lift the frame bearing the rolls 116 and 113, and when said arm 107 is lowered said finger will be correspondingly moved and said frame permitted to fall by gravity. Downward movement of said frame is limited by a suitable stop, as 120. The ink-reservoir consists of a doctor comprising a roll 121, and plate 122 engaging its periphery said plate being arranged tangential of the surface of the roll. The roll 121 is journaled in a stationary frame secured to the shaft 109. The roll 121 is designed to be rotated intermittently for a short period of time, then to pause for a short period of time and then to be again rotated intermittently, such intermittent rotations and pauses being alternate. To accomplish this result, as here shown, a ratchet-wheel 124 is secured to the roll 121 or to one of the journals thereof, which is engaged by a pawl 125 connected to a crank-pin 126 projecting from the side of a ratchet-toothed disk 127 journaled in an ear 128 on the frame, said disk being engaged by a pawl 129 loosely connected by a rocking-frame 130 mounted on said shaft 109. As said frame 130 is rocked the pawl 129 operates to revolve the ratchet-toothed disk step by step, and during a half revolution of said disk or thereabout, the pawl 125, which is connected to the crank-pin thereon, advances the ratchet-wheel 124 intermittently to turn the roll 121, and during the next half revolution thereof or thereabout said pawl 125 slips over the teeth of said ratchet-wheel 124, permitting said roll 121 to pause. As a means for transferring the ink from the roll 121 to the distributing-roll 116 a transfer roll 131 is employed, which is journaled in arms 132 extended from the rocking-frame 130. Movement of said frame 130 on the shaft 109 in one direction causes the transfer-roll to engage the roll 121 and in the opposite direction carries the transfer-roll into position to be engaged by the distributing-roll 116, when the latter occupies its lowermost position. The frame 130 is raised by means of a finger 133 arranged on one of the arms 115, which extends beneath one of said arms 132, so that when said arm 115 rises said finger will engage said arm 132 and lift the frame and move the trans-

fer-roll into engagement with the roll 121, and when said arm 115 falls the frame 130 will be permitted to fall by gravity. Downward movement of the frame 130 is limited by stop 134. It will thus be observed that the entire inking-mechanism is supported by a shaft extending over the top of the table. It is also herein designed to positively revolve the distributing-roll 116, and to accomplish this result one of its journals has a shaft 140 connected to it by a universal joint or otherwise, see Fig. 2, which is supported by a standard on the table, and said shaft has a belt-pulley 141, over which a belt 15 passes which passes over a belt-pulley 142 secured to a shaft 143, bearing a belt-pulley 144 over which a belt passes which passes over a belt-pulley 145 secured to the friction-disk 34. The shaft 140 is arranged and supported so as to permit the distributing-roll to be moved up and down by the frame bearing it.

The inking-mechanism is mounted on the stationary shaft 109, which is extended from the frame 123, and the extension of the shaft 109 is arranged sufficiently above the table to provide ample space beneath it for the work to be printed.

Having thus described my invention, what I claim as new and desire to secure by Letters Patent is:—

1. In an addressing-machine, a reversible receptacle adapted to contain a pile of stencil-plates and provided with locating means, and a support therefor provided with cooperating locating means and adapted to receive it in either position thereon it may occupy, substantially as described.

2. In an addressing-machine, a reversible receptacle adapted to contain a pile of stencil-plates composed of several upright posts and a reversible base-plate to which they are rigidly secured having dowel pins projecting from its under side, and a support provided with down holes and adapted to receive said reversible base-plate in either position thereon it may occupy, substantially as described.

3. In an addressing-machine, a receptacle adapted to contain a pile of stencil-plates, composed of several upright posts and an open base-plate to which they are rigidly secured, said base-plates having holes for attaching screws and having dowel-pins whereby it may be detachably connected to a support and its position thereon reversed, substantially as described.

4. In an addressing-machine, a table, a pair of horizontally arranged guide-ribs supported in elevated position thereon, a receptacle for a pile of stencil-plates having as a component part of it a base-plate which rests on the support bearing the guide-ribs and which is provided with a central opening whereby the pile of stencil-plates rests

on said guide-ribs and which base-plate is recessed at its under side to provide for the guide-ribs and also to provide for a sliding-pusher, a pusher sliding along on said guide-ribs and movable in said recess, and means for reciprocating said pusher, substantially as described. 70

5. In an addressing-machine, a receptacle adapted to contain a pile of stencil-plates and to be detachably connected to its support, comprising several upright posts and a pivotally connected guide-bar at the upper ends of said posts, movable into and out of upright position, against which the pile of stencil-plates is held while being moved into and out of the receptacle, substantially as described. 75

6. In an addressing-machine, a table, a recessed support thereon having guide-ribs at opposite sides of its recess, a pushing-plate contained in said recess having grooved sides to receive said guide-ribs, a receptacle adapted to contain a pile of stencil-plates, arranged above said support, and having an open bottom to enable the pile of stencil-plates to 85 rest on said guide-ribs, which bottom is recessed to provide for the entrance of a pushing-plate at one side of it and for the removal of the lowermost plate of the pile, at the opposite side of it, guide-bars arranged to form a slideway for the stencil-plates leading from said receptacle, arranged in line with the upper surface of said guiding-ribs, and means for reciprocating the pushing-plate, substantially as 90 described. 95

7. In an addressing-machine, the combination of a slideway for the stencil-plates, a pusher for pushing the stencil-plates along the slideway, an impression-roller for the stencil-plates, means for operating it, a reciprocating-frame for said pusher, operating-means for said frame movable into and out of engagement therewith, and means automatically controlling the engagement of 105 said operating-means with said frame, substantially as described.

8. In an addressing-machine, the combination of a slideway for the stencil-plates, a pusher for pushing the stencil-plates along 115 the slideway, an impression-roller for the stencil-plates, means for operating it, a reciprocating-frame for said pusher having a notched member, operating-means for said frame movable into and out of engagement 120 with the notched member thereof, and means for controlling the engagement of said operating-means with said notched member, substantially as described.

9. In an addressing-machine, the combination of a slideway for the stencil-plates, a pusher for pushing the stencil-plates along the slideway, an impression-roller for the stencil-plates, means for operating it, a reciprocating-frame for said pusher having a 125 130

notched member, operating-means for said frame movable into and out of engagement with the notched member thereof, a closing-plate for the notch in said member, and 5 means for moving said plate to cover and uncover said notch, substantially as described.

10. In an addressing-machine, the combination of a slideway for the stencil-plates, a 10 pusher for pushing the stencil-plates along the slideway, an impression-roller for the stencil-plates, means for operating it, a reciprocating-frame for said pusher having a notched member, operating-means for said 15 frame movable into and out of engagement with the notched member thereof, a closing-plate for the notch in said member, and intermittently operated-means for moving it to cover and uncover said notch, substantially 20 as described.

11. In an addressing machine, the combination of a slideway for the stencil-plates, a pusher for pushing the stencil-plates along the slideway, an impression-roller for the 25 stencil-plates, means for operating it, a reciprocating-frame for said pusher, operating-means for said frame movable into and out of engagement therewith, a controlling-device for controlling the engagement of 30 said operating-means and frame and having a rotatable-actuator, and means for intermittently revolving said actuator, substantially as described.

12. In an addressing-machine, the combination of a slideway for the stencil-plates, a 35 pusher for pushing the stencil-plates along the slideway, an impression-roller for the stencil-plates, means for operating it, a reciprocating-frame for said pusher, operating-means for said frame, movable into and out of engagement therewith, a controlling-device for controlling the engagement of 40 said operating-means and frame, a notched disk arranged to operate said controlling-device, and means for intermittently revolving 45 said disk, substantially as described.

13. In an addressing-machine, the combination of a slideway for the stencil-plates, a pusher for pushing the stencil-plates along 50 the slideway, an impression-roller for the stencil-plates, means for operating it, a reciprocating-frame for said pusher, operating-means for said frame, movable into and out of engagement therewith, a controlling-device for controlling the engagement of 55 said operating-means and frame, having a removable actuator, and means for intermittently revolving said actuator, substantially as described.

60 14. In an addressing-machine, the combination of a slideway for the stencil-plates, a pusher for pushing the stencil-plates along the slideway, an impression-roller for the 65 stencil-plates, means for operating it, a reciprocating-frame for said pusher, operat-

ing-means for said frame, movable into and out of engagement therewith, a controlling-device for controlling the engagement of said operating-means and frame, an actuator for said controlling-device, means for operating it, the co-operating parts of which may be disconnected, whereby said actuator 70 remains at rest, substantially as described.

15. In an addressing-machine, the combination of a slideway for the stencil-plates, a 75 pusher for pushing the stencil-plates along the slideway, an impression-roller for the stencil-plates, means for operating it, a reciprocating-frame for said pusher, operating-means for said frame movable into and 80 out of engagement therewith, a controlling-device for controlling the engagement of said operating-means and frame, automatic means for operating said controlling-device, and means for disconnecting said automatic 85 means, permitting the controlling-device to remain at rest, substantially as described.

16. In an addressing-machine, the combination of a receptacle adapted to contain a pile of stencil-plates, a slideway along which 90 said stencil-plates slide, a pusher for removing the lowermost plate of the pile and for moving it along the slideway, an impression-roller, means for operating it, a reciprocating-frame for said pusher, operating-means 95 for said frame movable into and out of engagement therewith, which is connected with the means for operating the impression-roller, and means controlling the engagement of said operating-means and 100 frame, substantially as described.

17. In an addressing-machine having a slideway along which the stencil-plates are moved, the combination of a stencil-plate support arranged at the end of the slideway, means for operating said support to reverse the stencil-plate supported by it, means for moving the stencil-plates along the slideway and for delivering them successively to 105 said support, a supporting-frame for said support having a plate-receiving recess at the bottom adapted to receive the reversed plates, and means for successively removing the reversed plates therefrom, substantially as described. 110

18. In an addressing-machine having a slideway along which the stencil-plates are moved, the combination of a stencil-plate support arranged at the end of the slideway, means for operating said support to reverse the stencil-plates supported by it, means for moving the stencil-plates along the slideway and for delivering them successively to 115 said support, a recessed frame for receiving the reversed plates, having openings at opposite sides, a sliding pusher for removing the reversed stencil-plates therefrom, and means for reciprocating said pusher, substantially as described. 120

19. In an addressing-machine having a 125

slideway along which the stencil-plates are moved, the combination of a stencil-plate support arranged at the end of the slideway, means for operating said support to reverse 5 the stencil-plate supported by it, means for moving the stencil-plates along the slide-way and for delivering them successively to said support, a frame for said support having a plate-receiving-recess beneath the support adapted to receive the reversed plates and having an exit, a sliding-pusher arranged to remove the reversed plates from said recess having a shoe at its forward end adapted to engage the stencil-plates, and 10 means for reciprocating said pusher longitudinally, substantially as described.

20. In an addressing-machine having a slideway along which the stencil-plates are moved, the combination of a circularly formed stencil-plate support arranged at the end of the slideway, means for operating it to reverse the stencil-plates, means for moving the stencil-plates along the slide-way and for delivering them successively 25 to said support, a frame containing said support comprising a base and upright side portions between which said stencil-plate support is located, and a spring-plate bearing against said stencil-plate support which follows its general contour as said stencil-plate support revolves, substantially as described.

21. In an addressing-machine having a slideway along which the stencil-plates are moved, the combination of a stencil-plate support arranged at the end of the slide-way, means for operating said support to reverse the stencil-plates supported by it, means for moving the stencil-plates along 30 the slideway and for delivering them suc-

cessively to said support, a frame bearing said support having a recess at the bottom adapted to receive the reversed plates and having an opening at the side, and a cover for said opening whereby access may be had 45 to the interior of the frame, substantially as described.

22. In an addressing-machine, a reversing-device for the stencil-plates, an intermittently revolving shaft to which it is attached, a rotary-reciprocating member, means connecting said member with said shaft, and means for reciprocating said member rotarily, substantially as described.

23. In an addressing-machine, a reversing-device for the stencil-plates, an intermittently revolving shaft to which it is attached, a rotary-reciprocating member, means connecting said member with said shaft, and longitudinally reciprocating 60 means for reciprocating said member rotarily, substantially as described.

24. In an addressing-machine, the combination of means for supporting a stencil-plate, a platen, an impression-roll, a yoke 65 in which said impression-roll is journaled, an arm to the extremity of which said yoke is attached by a single bolt permitting movement of the yoke with respect to the arm, and means for moving said arm to 70 move the impression-roll toward and from the platen, substantially as described.

In testimony whereof, I have signed my name to this specification, in the presence of two subscribing witnesses.

STERLING ELLIOTT.
